METHOD OF MAKING A SLIDER FOR A SLIDE FASTENER

Leonard M. Dorman, Meadville, Pa., assignor to Talon, Inc., a corporation of Pennsylvania

Application March 7, 1951, Serial No. 214,297

6 Claims. (Cl. 29—409)

This invention relates to slide fasteners, and particularly to an improved slider therefor and method of making the same.

It is one of the objects of the present invention to provide a novel method of attaching to the slider body a member which may serve as a means for connecting the pull member to the body, or as means for locking the slider automatically along the fastener elements at any desired point.

It is another object of the invention to provide a method of making a slider consisting of a minimum number of parts which can be easily and quickly assembled with a minimum number of operations.

It is a further object of this invention to provide a lock slider which is readily adaptable for manufacture from nonmetallic material, such as a plastic, and which is much more rugged and stronger than plastic lock sliders made by other known methods.

It is still another object of the present invention to provide such a slider wherein the pull member has a solid trunnion or pivotal portion thereby eliminating any danger of disengagement of the trunnion from the slider body and, at the same time, possesses all the normal functions and advantages of a good automatic lock slider.

Various other objects and advantages of this invention will be more apparent in the course of the following specification, and will be particularly pointed out in the appended claims.

In the accompanying drawings, there is shown for the purpose of illustration, several embodiments which my invention may assume in practice.

In these drawings:

Fig. 1 is a plan view of a slide fastener having the improved slider of my invention incorporated therewith;

Fig. 2 is a sectional view taken on line 2—2 of Fig. 1;

Fig. 3 is a sectional view taken on line 3—3 of Fig. 2;

Fig. 4 is a sectional view taken on line 4—4 of Fig. 2; and

Fig. 5 is a side elevational view of a modified form of slider in accordance with the present invention.

Referring more particularly to the drawings, there is shown in Fig. 1, a conventional type slide fastener comprising a pair of stringer tapes 2 having a series of opposed spaced-apart interlocking fastener elements 3 arranged along the opposed beaded edges thereof. There is arranged on the fastener elements, a slider 4 constructed in accordance with the present invention, for longitudinal movement in either direction therealong to open and close the fastener in a well-known manner.

Such a slider consists generally of a slider body having spaced-apart upper and lower wing portions 5 and 6, respectively, which are interconnected at one end thereof by a neck portion 7 and having inwardly extending oppositely disposed marginal flanges 8 at each side so as to provide substantially a Y-shaped channel in the slider body through which the fastener elements pass during the opening and closing movement of the slider. This

2

slider body is made preferably of a moldable plastic material, such as nylon, but may be made from metal or any other suitable material.

According to the present invention, there is arranged on the outer side of the upper wing 5 centrally thereof, a pair of spaced-apart lugs 9 and 10. On either side of the lug 9, there is arranged an outwardly extending projection 12 with each being preferably beveled, as at 13, at the outer upper ends thereof, as shown in Fig. 3, for a purpose hereinafter to be described. Also, on the other or lower lug 10, there is arranged to either side thereof a similar outwardly extending projection 14 both of which also are preferably beveled, as at 15, at their outer upper ends, as shown in Fig. 4.

There is provided an elongated cap-like member 16 having a top wall 17, end walls 18 and 19, and side walls 20 and 21 which are slightly yieldable for assembling purposes as will be described. At the upper end of this cap-like member, there is arranged in the side walls 20 and 21 thereof, a pair of opposed apertures 22 in which the opposed projections 12 carried by the lug 9 are disposed. In the side walls 20 and 21 at the lower end of the cap-like member, there is likewise arranged a pair of opposed apertures 23 in which the opposed projections 14 carried by the lug 10 are disposed. In case the slider is to be used as a lock slider, the lower apertures 23 are substantially larger than the projections 14, as shown in Figs. 2 and 4, so as to permit movement of the lower end of the cap-like member 16 relative to the slider body as will be described. This cap-like member is also preferably made of a plastic material, such as nylon, but may be made from any other suitable material.

There is arranged with the side wall 21 of the cap-like member 13, a locking projection 24 which normally extends through an opening 25 in the upper wing 5 of the slider body into the channel therein and into engagement with the fastener elements 3 to lock the slider in a well-known manner.

In the upper end of the lug 9, there is arranged in an opening therein, a leaf-like spring member 26 with the free end thereof abutting a shoulder 27 arranged on the inner wall 18 of the cap-like member 16. It is the purpose of this spring member to urge normally the cap-like locking member to its locked position in a manner well-known.

There is provided a pull member 28 which may be of any convenient form and consists preferably of a flat member having a large rectangular-shaped opening 29 at its one end so as to provide a pair of spaced-apart leg portions 30 terminating in a solid pivotal or trunnion portion 31 at its extreme end by means of which the pull is pivotally attached to the slider as will be presently explained. This trunnion or pivotal portion 31 is disposed loosely in the space between the lugs 9 and 10 with the trunnion portion extending to either side of the lugs so as to be disposed in a relieved or cutaway portion 32 in the side walls of the cap-like member, as more clearly shown in Fig. 2 of the drawings. This trunnion portion is maintained in such position by the cap-like member 16 which acts as a pull attaching means as well as a locking means.

When the pull member is manipulated to operate the slider, the trunnion or pivotal portion 31 is forced against the bottom edges of the cutaway portion 32 of the side walls of the cap-like member, thereby moving it about its pivotal connection with the projection 12 of the lug 9 against the action of the spring 26 thereby moving the locking projection 24 out of the channel of the slider and out of engagement with the fastener elements therein so as to permit free movement of the slider therealong in a manner well known to those skilled in the art.

The slider of my invention is assembled in the following manner. As has been previously stated, the slider body is preferably molded from a suitable material with the lugs 9 and 10 and projections 12 and 14 integrally molded therewith. After such a slider body is provided, the spring member 26 is positioned in the opening in the end of the lug 9, and then the pivotal or trunnion portion 31 of the pull member 28 is disposed between the lugs 9 and 10. The cap-like member 16 is then positioned on the lugs 9 and 10 and forced toward the slider body, as shown in Fig. 2. In forcing the cap-like member over the lugs, the side walls of the cap-like member will yield and spread sufficiently so as to permit the side walls to pass over the ends of the projections 12 and 14 due to the beveled upper ends 13 and 15 of the projections 12 and 14, respectively. When the cap-like member is fully seated on the lugs, the side walls of the cap-like member will spring back to their normal positions and the projections 12 will be disposed in the apertures 22, and the projections 14 will be disposed in the apertures 23 so as to lock securely the cap-like member in position on the lugs 9 and 10 with the trunnion portion of the pull member disposed loosely between the cap-like member and the upper wing of the slider body. In other words, the cap-like member is forced over the lugs and the outwardly projecting portions carried thereby and moved to position by a snapping action. This completes the assembly of the slider.

In Fig. 5 of the drawings, there is shown a slight modification of the invention wherein a non-locking slider is shown. In this construction, the locking projection 24 and spring 26 have been eliminated and the lower apertures 33 in the side walls of the cap-like member are slightly smaller than the lower apertures 23 in the cap-like member 16 of the lock slider construction as has been previously described so as to eliminate any movement between the cap and the slider body which, of course, is not necessary in this type of slider. Otherwise, this construction is the same as that shown for the lock slider and it is assembled in the same manner.

While I have shown and described several embodiments which my invention may assume in practice, it will be understood that these embodiments are merely for the purpose of illustration and description, and that other forms may be devised within the scope of my invention as defined in the appended claims.

What I claim as my invention is:

1. The method of making a slider for slide fasteners of the class described comprising the steps of forming a slider body having spaced-apart wing portions secured together at one end thereof so as to provide a channel therebetween, forming at least one lug on the outer surface of one of said wing portions having an outwardly extending projection arranged on either side thereof, providing a cap-like member having opposed apertures arranged in the side walls thereof, and positioning said cap-like member on said lug and forcing it to position thereon so that said projections are disposed in said apertures whereby said cap-like member is securely held in position thereon.

2. The method of making a slider for slide fasteners of the class described comprising the steps of forming a slider body having spaced-apart wing portions secured together at one end thereof so as to provide a channel therebetween, forming a pair of spaced-apart lugs on the

outer surface of one of said wing portions with each having an outwardly extending projection arranged on either side thereof, providing a cap-like member having two pairs of opposed apertures arranged in the side walls thereof, and positioning said cap-like member on said lugs and forcing it to position thereon so that said projections are disposed in said apertures whereby said cap-like member is securely held in position thereon.

3. The method of making a slider for slide fasteners of the class described comprising the steps defined in claim 2, and including forming a beveled surface on the outer ends of the outwardly extending projections on the lug so as to aid in guiding and positioning the projections into the apertures of the cap-like member.

4. The method of making a slider for slide fasteners of the class described comprising the steps defined in claim 2, and including forming a beveled surface on the lower inner edges of the side walls of the cap-like member opposite the apertures therein so as to aid in positioning and guiding the projection on the lugs in said apertures.

5. The method of making a slider for slide fasteners of the class described comprising the steps of forming a slider body having spaced-apart wing portions secured together at one end thereof so as to provide a channel therebetween, forming a pair of spaced-apart lugs on the outer surface of one of said wing portions with each having an outwardly extending projection arranged on either side thereof, providing a cap-like member having yieldable side walls in which there are arranged two pairs of opposed apertures with the pairs spaced apart a distance substantially equal to the distance between the projections on said lugs, the distance between said side walls being slightly greater than the width of said lugs, positioning said cap-like member on said lugs and forcing it toward the slider body over said lugs whereby the side walls of said cap-like member will yield slightly due to the camming action of said projections thereby permitting said side walls to pass over the ends of said projections with said projections adapted to be disposed finally in the respective apertures after said cap-like member has been moved to its innermost position on said lugs and the side walls have assumed their normal position.

6. The method of making a slider for slide fasteners of the class described, the steps as defined in claim 5, and including forming a beveled surface on the outer ends of the outwardly extending projections so as to aid in the camming action of the projections on the side walls of the cap-like member when it is being snapped to position on the lugs.
